(57) **CLAIM**

The ornamental design for a hair trimmer, as shown and described.

DESCRIPTION

FIG. 1 is a top perspective view of the present hair trimmer;
FIG. 2 is a right side view thereof;
FIG. 3 is a left side view thereof;
FIG. 4 is a front view thereof;
FIG. 5 is a rear view thereof;
FIG. 6 is a bottom plan view thereof;
FIG. 7 is a top plan view thereof; and,
FIG. 8 is a bottom perspective view thereof.
In the drawings, the broken lines illustrate portions of the hair trimmer that form no part of the claimed design.

1 Claim, 5 Drawing Sheets
